UNITED STATES PATENT OFFICE

PERCY HORSFALL, OF PINGELLY, WESTERN AUSTRALIA, AUSTRALIA

BAG LOADER

Application filed July 14, 1928, Serial No. 292,780, and in Australia July 25, 1927.

This invention relates to a bag loader.

The conventional type of bag loader fixed at the side of a waggon is unsuitable for use with motor trucks, as it requires a horse for its operation.

5 The present invention relates to a bag loader which is so designed that it can be manually operated without undue effort. The device can be used at a desired position on the sides or rear of the truck.

10 An important feature of the invention consists of a lever arrangement, whereby the fulcrum about which the effort is exerted can be raised as the bag is moved up the loader.

15 The invention will, however, more readily be understood by reference to the accompanying drawings, in which:—

Figure 1 is a perspective view of the bag loader in the inclined position as it will appear against a truck;

Fig. 2 is a side elevation showing the bag loader in its lowermost or loading position;

Fig. 3 is a similar view on a larger scale, in which the dotted lines show the position of 25 the bag carrier shortly after the raising effort is commenced;

Fig. 4 is a perspective view of the arrangement constituting the movable fulcrum and appurtenant parts;

30 Fig. 5 is a side elevation showing the relative disposition of the carrier, link, and working levers as they will appear when a lifting effort is about to be applied;

Fig. 6 is another view of the parts shown 35 in Fig. 5, except that the lifting effort has now been applied, with the result that the carrier has been moved to a higher position;

Fig. 7 is a perspective view showing the 40 sliding U-shaped support that engages the carrier or cradle hooks;

Fig. 8 is a perspective view showing the relative disposition of the longitudinal angle iron frame members;

Fig. 9 is a side elevation showing the relative disposition of the working levers, links 45 and pawls, and;

Fig. 10 is a side elevation showing the carrier and its appurtenant parts as they will appear when the tipping position is reached.

50 Referring to these drawings, 10, 11, 12 and

13 are longitudinal angle iron frame members. Of the foregoing, the members 10 and 11 have their open angles facing each other, and at each end are conveniently connected to a wooden block 10' and 11' or other support, so as to maintain them in the correct relative position. The angle iron members 12 and 13 are spaced inside the members 10 and 11, so that one of their flat faces is turned upwardly. A longitudinal channel or space 55 is left at each side between each of the corresponding pairs of angle iron members. This is made possible by using a plurality of metal connecting stops, such as 14, 15 and 16. Adapted to slide upwardly in the space formed between the inner angles of the inner angle iron members and the corresponding lower faces of the outer angle iron members, is a U-shaped support 17. Such support has its downward movement limited 60 by one of the stops, such as 16, which is made so as to project inwardly to a greater extent than the other stops. There are two short angle iron members 18 and 19 which form part of what may be termed the movable fulcrum assembly. Each of these short angle iron members is positioned so that one of its faces will be on the under-side of the upper faces of the inner angle iron frame members 12 and 13. The angle iron members 18 and 19 are held in their relative spaces by means of connecting bars 20 and 21. A transverse rod 22 freely passes through each of the short angle iron members and connected to such rod on one side is a pawl 23 that is 65 adapted to move in the channel or space between the angle iron frame members 10 and 12, whereby it will engage the metal stops, such as 14, 15, or 16, according to its position, and therefore hold the movable fulcrum assembly against downward movement. The transverse rod 22 also has connected a short pawl-releasing lever 24. There is a working arm 25 of the apparatus which is connected to or is extended as two parallel working levers 70 26 and 27, suitably stayed by transverse bars. A fulcrum rod 28 passes through the short angle iron members 18 and 19 and through the working levers 26 and 27. The ends of the working levers are pivoted to two parallel 75 100

connecting links 29 and 30, that in turn are pivoted to two curved carrier supports, of which only one, namely, that referenced 31, is visible in the drawings. The pivotal connection of the connecting links 29 and 30 to the curved carrier supports, such as 31, is effected by a transverse rod 32 passing through such members. The said transverse rod has attached a pawl 33 adapted to engage the metal stops previously alluded to. Metal rollers 34 and 35 are carried by an axle 35' loosely passing through the lower portion of the curved carrier supports, such as 31, the rollers being so spaced as normally to track on the upper face of the angle iron frame members 12 and 13. It is to be herein noted that these rollers 34 and 35 at times travel upon the track formed by the bars 12 and 13 and that the levers 26, 27, 29 and 30 will swing upon their pivoted connections between these bars 12 and 13 so that when the axle 35' contacts with these levers, the axle will be permitted to ride thereupon. Attached to the ends of the curved carrier supports, such as 31, there are curved cradle or carrier members 36 and 37 connected by transverse members 38, 39 and 40. Attached to the transverse member 39 are holding hooks 41 and 42. At the upper end of the angle iron frame members there is a transverse end bar 43.

The apparatus operates as follows:

When the cradle or carrier is in its lowermost or loading position, it will be placed as is shown in Figs. 2 whereat the movable fulcrum is retained against downward sliding movement by the pawl 23 engaging one of the stops. The bag is dumped or rolled on to the carrier or cradle and the working arm 25 is raised, which produces the result illustrated in dotted lines in Fig. 3, namely, that the axle 35' is engaged by the levers 26 and 27 and the carrier is raised to a position whereat the rollers 34 and 35 leave the tracks 12 and 13. This axle 35' will then ride upon the curved levers 26 and 27 and the carrier will move by gravity until the rollers 34 and 35 again engage their respective tracks 12 and 13 at points above the fulcrum point of said levers which is provided by the rod 28. Almost simultaneously the holding hooks 41 and 42 take up a position on the under-side of the sliding U-shaped support 17. When the working arm 25 is pulled or pushed downwardly, the effect is that the working levers 26 and 27 fulcrum about the rod 28 and exert an effort on the connecting links 29 and 30, and so to the carrier or cradle, which is pushed upwardly. This action is effected by the rollers 34 and 35 running on the track formed by the angle iron frame members 12 and 13. When the working arm has been pushed or pulled downwardly, it is again raised. The first effect is that the cradle or carrier is maintained at its new raised position by reason of the fact that the pawl

33 is held against one of the metal stops, such as 14, 15 or 16. The next effect is that what may be termed the fulcrum assembly is slid upwardly, or in other words, the fulcrum is raised to a higher level. This fulcrum assembly, which is illustrated in Fig. 4, consists of the short angle iron members 18 and 19, the fulcrum rod 28, the connecting bars 20 and 21, transverse rod 22, pawl 23, and pawl-releasing lever 24. The whole of such assembly is raised and is held in a new but higher position by reason of the fact that the pawl 23 bears against a higher metal stop. The next downward pull on the working arm 25 results in the cradle or carrier being pushed to a still higher position. The next upward lift of such working arm results in the fulcrum being raised to another higher point. A stage is reached when on commencing or during the downward pull of the working arm 25, the cradle or carrier has gone as far as is permitted, namely, as illustrated in Fig. 10, the ends of the hooks 41 and 42 abut against the end bar 43. Further downward effort on the working arm 25 results in the cradle or carrier being turned, as is shown in dotted lines in Fig. 10. In other words, it results in the bag being dumped at the higher level desired. When the dumping angle has been reached, the hooks 41 and 42 have disengaged themselves from the sliding U-shaped support 17 and on releasing the pawl-releasing lever 24, the carrier or cradle can, by a very slight effort, be made to take up the initial or loading position illustrated in Figs. 5 and 6. When it is desired to dump at a higher level, the apparatus is inclined at a steeper angle.

I claim:—

1. A bag loader comprising a portable frame, a carrier adapted to travel upon said frame, a manually operable lever, connection means between said lever and carrier for causing said carrier to travel upon said frame with operation of the lever, a movable fulcrum for said lever slideable upon said frame, and means for fixedly holding said movable fulcrum at various points upon said frame. 105

2. A bag loader comprising an inclined track, a bag carrier adapted to travel upon said track, a movable fulcrum carried by said track, a lever connected to said fulcrum and having means operatively engaged with the bag carrier whereby when power is applied to said lever the bag carrier will be caused to move upwardly upon said track, and means for causing said carrier to dump the bag carried thereby upon reaching the uppermost position upon said track. 110

3. A bag loader comprising in combination a portable frame, a track arranged upon said frame, a bag carrier, rollers for mounting said bag carrier upon said track, a working lever having a movable fulcrum, means for opera- 130

5 tively connecting said lever to said bar carrier, and pawl means between said lever and track whereby when said working lever is moved upwardly upon said track and then moved in an opposite direction, it will cause its fulcrum to move at higher points upon said track.

4. A bag loader comprising in combination a portable frame, an inclined track arranged upon said frame, a bag carrier adapted to travel upon said track, a movable fulcrum adapted to assume various positions upon said frame, a lever connected to said fulcrum, links for connecting said lever to said carrier and means for retaining said fulcrum at various positions upon said frame.

5. A bag loader comprising in combination an inclined track, a carrier adapted to move upon said track, means for manually causing said carrier to move upwardly upon said inclined track, means for retaining said carrier at various positions upon said track and means for preventing said carrier from overbalancing backwardly during its upward 25 travel upon said track.

6. A bag loader comprising in combination an inclined track, a bag carrier, rollers for supporting said bag carrier upon said track, a holding member movably mounted upon said track, and hooks carried by said carrier for engagement with said movable holding member for preventing the carrier from swinging upon said rollers which support the same upon the inclined track.

35 7. A bag loader comprising in combination an inclined track, a bag carrier, rollers for supporting said carrier and adapted to travel upon said track, a movable holding member, hooks carried by said carrier and adapted at 40 times to engage said movable holding member so as to prevent backward overbalancing of the carrier, and means carried by the track engageable by said hook whereby the latter may be released from said movable holding member.

55 8. A bag loader comprising in combination an inclined track, a bag carrier movable upon said track, a movable holding member slidably mounted upon said track, hooks carried by said bag carrier and adapted to engage said movable holding member, and means for simultaneously releasing said hooks from said movable holding member and tipping said bag carrier whereby the bag may be discharged therefrom.

9. A bag holder comprising in combination parallel and longitudinal frame members, a track arranged upon said frame members, a carrier adapted to be carried upon said track, two connecting members capable of sliding relative to the longitudinal frame members, a fulcrum rod passed through said two connected members, a working arm connected to said fulcrum rod and a pair of

working levers connecting said working arm with said bag carrier.

10. A bag loader comprising in combination a portable track, a bag carrier adapted to travel upon said track, a movable fulcrum adapted to travel upon said track, a working arm supported by said movable fulcrum, a pair of working levers connecting said working arm with said carrier, and a pawl carried by said movable fulcrum and adapted to engage said track for retaining said movable fulcrum from travelling in one direction.

11. A bag loader comprising in combination an inclined track, a bag carrier adapted to travel upon said track, a movable fulcrum adapted to travel upon said track, a working lever carried by said fulcrum, a pawl carried by said movable fulcrum and adapted to engage said track to prevent downward movement of said movable fulcrum, means for connecting said carrier with said working lever and pawls carried by said carrier for engagement with said track whereby the carrier will be prevented from downward movement thereupon.

12. A bag loader comprising in combination a track, a bag carrier comprising a cradle adapted to travel upon said track, a working lever, links connecting said working lever with the cradle of the bag carrier, a travelling fulcrum for said working lever and means for retaining said travelling fulcrum at various positions upon said track.

13. A bag loader comprising in combination a pair of inclined members, a track secured upon each inclined member, stops carried by said track, a bag carrier adapted to travel upon said track, a movable fulcrum, a working lever carried by said fulcrum, means for operatively connecting said lever with said carrier and pawls carried by said carrier and movable fulcrum for engagement with said stops whereby the carrier and movable fulcrum may be retained in various positions upon said track.

14. A bag loader comprising in combination a support consisting of a pair of spaced and parallel angle bars, an angle bar secured to each of said spaced angle bars of the support forming a track, a bag carrier adapted to travel upon said track, said bag carrier comprising a pivotally supported cradle, a pivotally supported working lever, links connecting said lever with said cradle, a sliding member, hooks carried by said cradle for engaging said sliding members and means whereby when said carrier is forced to one end of said track the hooks will be disengaged from said sliding member and the cradle tilted whereby a bag supported thereby may be dumped therefrom.

15. A bag loader comprising in combination a portable support, an inclined track arranged upon said support, a plurality of stops connecting said track from said sup-

port, a carrier adapted to travel upon said track, a movable fulcrum adapted to travel upon said track, a working lever supported by said fulcrum, means for connecting said working lever with said carrier, a U-shaped sliding member arranged upon said frame, hooks carried by said carrier and adapted to engage said U-shaped sliding member and pawls carried by said carrier and movable fulcrum for engagement with said stops whereby they may be retained at various positions upon said track.

Dated this 30th day of May, 1928.
